UNITED STATES PATENT OFFICE

2,441,868

APPARATUS FOR MASSAGING PORTIONS
OF THE BODY

Lola A. Casnati, New York, N. Y.

Substituted for abandoned application Serial No.
560,562, October 27, 1944. This application
April 26, 1947, Serial No. 744,255

3 Claims. (Cl. 128—40)

1

This invention relates to new and useful improvements in blood circulating devices in the nature of face and body massaging articles.

This is a substitute for my abandoned application filed on October 27, 1944, Serial Number 560,562.

More particularly, the invention proposes a new and improved blood circulating device which is characterized by a cup-like member having a hollow stem through which air may be evacuated. It is proposed to connect a rubber tube with said stem. A rubber bulb is connected with said tube and is provided with a one-way valve for discharging air when said bulb is squeezed.

It is proposed that the cup-like member be placed and moved over the surface of the face or other parts of the skin to be massaged. Simultaneously, the rubber bulb is compressed and allowed to expand. Then it is compressed and allowed to expand again, and this operation is continued as the cup-like member is moved along the skin.

The invention proposes modifications in which the cup-like members are of different shapes or designs, and in which an air bleed element is associated with each rubber bulb and is connected with means by which it may be rapidly opened and closed for setting up air vibrations within each cup-like member to facilitate blood circulation.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a side elevational view of a face massaging and blood circulating device constructed in accordance with this invention.

Fig. 2 is a fragmentary enlarged sectional view taken on the line 2—2 of Fig. 1.

Fig. 3 is a transverse enlarged sectional view of another portion of Fig. 1 at an area where the bulb connects with the rubber tube.

Fig. 4 is a fragmentary enlarged sectional view taken on the line 4—4 of Fig. 1.

Fig. 5 is a fragmentary enlarged sectional view taken on the line 5—5 of Fig. 1.

Fig. 6 is a side elevational view of a blood cir-

2

culating device constructed in accordance with another form of this invention.

Fig. 7 is an enlarged vertical sectional view through the rubber bulb illustrated in Fig. 6.

Fig. 8 is a fragmentary enlarged horizontal sectional view taken on the line 8—8 of Fig. 7.

Figs. 9 and 10 are side elevational views of other modified face massaging devices constructed in accordance with this invention.

10 The face massaging and blood circulating device, as illustrated in Figs. 1—5 inclusive, includes a cup-like member 10 having a hollow stem 11 through which its air may be evacuated. This member 10 is formed of glass or thermo-plastic material. The stem 11 has its rear end 12 bent at right angles. A rubber tube 13 is engaged on the rear end 12 of the stem 11. A rubber bulb 14 is coupled to the rear end of the rubber tube 13. More particularly, the rubber bulb 14 is mounted upon a metal or other bushing 15 having an externally threaded section 16. This bushing 15 also has a stem portion 17 upon which the end of the tube 13 is forced. An annular member 18 is rotatively mounted on the end of the tube 13 and is held in a rotative position by and between several collars 19 and 20. This annular member 18 has a pair of fingers 21 provided with threads threadedly engaging the threads 16.

The bulb 14 has an annular net member 22 mounted around its central portion for engagement by the fingers when the bulb 14 is squeezed. The bulb 14 is also provided with a one-way valve 23 arranged to allow the air to freely discharge from the bulb, but to automatically close and to prevent air from entering the bulb. This valve 23 is in the form of a tubular casing 24 set into an opening 25 formed in the end of the bulb 14.

A sheet-like flexible washer 26, preferably of 40 rubber is mounted in the casing 24 and has a central passage 27 for the air. A rigid washer 28 is mounted against the inner face of the washer 26 and is provided with air passages 29 offset from the air passage 27. When the bulb 14 is

45 squeezed the air will be forced through the passages 29, the flexible washer 26 will expand upwards and the air will escape through the passage 27. Air can not flow inwards of the valve, because the flexible washer 26 will engage against 50 and close the openings 29.

The operation of the blood circulating device is as follows:

With one hand the cup-like member 10 is pressed against and moved along the face or other parts of the body or a person being mas-

saged. With the other hand the masseur squeezes the bulb 14 and allows the bulb 14 to expand. The suction created in the cup 10 will lift the flesh and breaking the suction will drop the flesh, and then continued operation will lift the flesh and drop the flesh, as the cup is moved along the body and as the suction within the cup is made and broken. This circulates the blood in the vicinity.

In Figs. 6-8 a modified form of the invention is shown which is very similar to the prior form, distinguishing in the fact that the cup-like member 30 is of square shape in transverse cross section. It is provided with a tubular stem 31. The bulb 14 has its one way valve offset to one side. A tubular casing 32 is mounted at the top of the bulb 14. This tubular casing has several air outlet passages 33. A rotating valve 34 controls the passages 33. This rotating valve 34 is turned by a stem 35 which is provided with a spur gear 36 meshing with a rack 37 mounted diametrically through and on the interior face of the wall of the bulb 14. The rack 37 is slidably mounted in a tubular member 38 which is supported on an opposed point of the wall of the bulb 14. A spring 38 within the tubular member 38 normally urges the rack 37 outwards. A bearing strip 40 is mounted around the tubular member 38 and forms a bearing for the stem 35 so that the gear 36 is rotatively supported.

In other respects this form of the invention is similar to that previously shown and like reference numerals identify like parts in each of the several views.

The operation of this form of the invention is similar to the first form in that the cup 30 is moved along one's body, while the bulb 14 is pressed and allowed to expand, and then pressed again. However, it distinguishes in the fact that when the bulb 14 is compressed, the air will discharge through the one way valve which controls the passage 25. When the bulb 14 is compressed the rack 37 will be forced into the casing 32 which drives the stem 35 for turning the rotary valve 34 in one direction. When the bulb 14 is released it automatically expands. The spring 39 assists the expansion of the bulb and furthermore forces the rack 37 outwards. This motion drives the stem 35 which drives the rotary valve 34. The rotary valve 34 will rapidly open and close the air passages 39. Momentum of the stem will maintain rotation while the valve 34 passes closed spots in the casing 32, so that there is a step-like entrance of air into the bulb 14. This vibrates or oscillates the air contained in the cup-like member 30. The vacuum will be broken in steps and the jerky steps will assist the blood circulating action.

In Fig. 9 the cup-like member 50 is shown to be perpendicular with and attached to one end of a rigid connecting tube 51 which acts as a handle. The other end of the connecting tube 51 is provided with a rubber or other compression bulb 52 which may be compressed to discharge air or water through the cup 50.

In Fig. 10 the cup-like member 50' is in alignment with the hollow stem 51' and with the bulb 52'.

In other respects this form of the invention is similar to that previously shown and like reference numerals identify like parts in each of the several views.

5 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent, is:

- 15 1. Apparatus for massaging portions of the body, comprising a cup-like member having a hollow stem through which its air may be evacuated, a rubber tube connected with said stem, and a rubber bulb connected with said tube having a one way valve for discharging air when said bulb is squeezed, an air bleed element for said rubber bulb, and means for rapidly opening and closing said air bleed element for setting up air vibrations within said cup-like member.
- 20 2. An apparatus for massaging portions of a body comprising a cup-like member having a hollow stem through which its air may be evacuated, a rubber tube connected with said stem, and a rubber bulb connected with said tube having a one way valve for discharging air when said bulb is squeezed, an air bleed element for said rubber bulb, and means for rapidly opening and closing said air bleed element for setting up air vibrations within said cup-like member, including a rotary valve for controlling the entrance of air to said bulb, and a rack moved by the contraction and expansion of the rubber bulb for driving said valve.
- 25 3. An apparatus for massaging portions of a body comprising a cup-like member having a hollow stem through which its air may be evacuated, a rubber tube connected with said stem, and a rubber bulb connected with said tube having a one way valve for discharging air when said bulb is squeezed, and air bleed element for said rubber bulb, and means for rapidly opening and closing said air bleed element for setting up air vibrations within said cup-like member, including a rotary valve for controlling the entrance of air to said bulb, and a rack moved by the contraction and expansion of the rubber bulb for driving said valve.
- 30 4. An apparatus for massaging portions of a body comprising a cup-like member having a hollow stem through which its air may be evacuated, a rubber tube connected with said stem, and a rubber bulb connected with said tube having a one way valve for discharging air when said bulb is squeezed, and air bleed element for said rubber bulb, and means for rapidly opening and closing said air bleed element for setting up air vibrations within said cup-like member, including a rotary valve for controlling the entrance of air to said bulb, and a rack moved by the contraction and expansion of the rubber bulb for driving said valve.
- 35 5. An apparatus for massaging portions of a body comprising a cup-like member having a hollow stem through which its air may be evacuated, a rubber tube connected with said stem, and a rubber bulb connected with said tube having a one way valve for discharging air when said bulb is squeezed, and air bleed element for said rubber bulb, and means for rapidly opening and closing said air bleed element for setting up air vibrations within said cup-like member, including a rotary valve for controlling the entrance of air to said bulb, and a rack moved by the contraction and expansion of the rubber bulb for driving said valve, said rack being connected with and driving a gear, and a stem connected with said gear and with said rotary valve.
